Fig.3

FIG. 1 is a perspective front view of a bookcase embodying my new design;

FIG. 2 is a top view of same; and

FIG. 3 is a front-elevational view thereof.

Close surface shading is indicative of contrastingly dark coloring.

The essential features of my design reside in those portions which are shown in full lines on the drawing.

I claim:

The ornamental design for a bookcase, as shown and described.
